United States Patent Office

Des. 175,741
Patented Oct. 4, 1955

175,741

BRASSIERE

William Rosenthal, Bayville, N. Y., assignor to Maiden Form Brassiere Co., Inc., New York, N. Y., a corporation of New York

Application February 1, 1955, Serial No. 34,313

Term of patent 14 years

(Cl. D20—4)

The figure is a perspective view of a brassiere showing my new design.

The back of the brassiere is of conventional configuration.

I claim:

The ornamental design for a brassiere, as shown and described.
